UNITED STATES PATENT OFFICE.

WILLIBALD GRUN, OF FRANKFORT-ON-THE-MAIN, GERMANY.

STEAM-TURBINE.

1,128,132.

Specification of Letters Patent. Patented Feb. 9, 1915.

Application filed January 4, 1913. Serial No. 740,180.

To all whom it may concern:

Be it known that I, WILLIBALD GRUN, chief engineer, a subject of the Emperor of Germany, and a resident of Frankfort-on-the-Main, in the Empire of Germany, have invented certain new and useful Improvements in Steam-Turbines, of which the following is a specification.

This invention relates to steam turbines comprising one or more groups of wheels which can be shut down separately from the whole turbine.

In steam turbines comprising one or more groups of wheels which can be separately shut down, there are difficulties in making the closure-members, joints at the shafts, and the like perfectly tight. Therefore steam can enter into the groups of wheels which are shut down, and when such steam flows through the blades considerable resistance is offered by it to the motion of the idle group of wheels, the result being a material loss of work.

A primary object of my invention is to obviate this defect. To this end, according to this invention, the steam admission ports of the shut-down groups of wheels are able to be connected with the exhaust chamber or with the condensing apparatus, in order that any steam which does leak through may be directly conducted away and produce no detrimental effect. The connection of the steam admission ports of the shut-down groups of wheels with the corresponding exhaust port or with the condensing apparatus may be established directly by hand or automatically when closing the member controlling the admission of steam, this member being positively connected with that member which controls the connection of the steam admission ports of the groups of wheels which can be shut down with the exhaust or condensing apparatus.

Two illustrative embodiments of my invention are represented, by way of example, in the accompanying drawing, wherein:

Figure 1 is a vertical section through a turbine having groups of wheels which can be shut down, and comprising one combination of valves according to my invention; Fig. 2 is a vertical section, enlarged, showing a modified combination of valves, and Fig. 3 is a like view of the auxiliary valve shown in Fig. 1.

Referring first to Fig. 1, the two groups of wheels 1, 2, which can be shut down,

are arranged in a known manner on a common shaft 3 at the two sides of the common exhaust port or chamber 4, and are provided with separate steam supply pipes 5, 6 under the control of a common main stop-valve 7. For shutting down the one group of wheels 1 an auxiliary stop valve 8 is provided whose casing is shown connected by way of the pipe 9 with the exhaust chamber 4, so that any steam leaking through the closed valve can flow away and does not prejudicially influence the running of the idle group 1. Consequently, when running idle the group 1 offers very little resistance, whereby the mechanical efficiency of the steam turbine is improved.

Referring now to Fig. 2, in the form of the change-over member shown here the two branches 10, 11, are for connecting the steam supply pipe to the two groups 1, 2, the steam flowing in through the lower end of the casing. The steam is shut off from the individual groups of wheels by means of the piston valves 12, 13 mounted on a spindle 14 which can be moved up and down by means of a hand-wheel, not shown, fixed on the spindle, or can be operated automatically directly by or indirectly from the governor, for example. The pistons 12, 13 control ports 15, 16 which are connected with the admission ports 10, 11.

The spindle 14 has a longitudinal bore 17 extending down into the hub 20 of the upper piston 12, and transverse passages 18 under the hub open into this bore. These passages 18 are connected by way of a recess 19 in the hub 20 and by way of a duct 21 with the port 15 in the casing of the valve when the piston 12 takes up the closed position shown in the drawing, in which the group of wheels connected to the admission port 10 is shut down. Additional transverse passages 22 open into the longitudinal bore 17 of the spindle; these lead to a recess 23 in the spindle-guide 33 on the valve cover 34, into which opens one end of the by-pass pipe 9 whose other end is connected as in Fig. 1 to the exhaust chamber 4.

As long as both groups of wheels are in action the piston 12 and the spindle 14 occupy a position in which the connection of the port 15 with the pipe 9 is interrupted as the transverse holes 22 are then surrounded by that part of the guide 33 which is above the recess 23. Now when the piston 12 is shifted into the position shown in Fig. 2

when shutting down one group of wheels, any steam leaking past the piston-valve 12 and its seat must flow from the groove 15 through the duct 21, the holes 18 the bore 17 5 and the holes 22 and by way of the recess 23 and the pipe 9 the shortest way to the exhaust 4. Any other steam leaking in on the admission side will likewise flow away along the by-pass without having to flow through 10 the group of wheels. No special manipulation for leading away the leakage steam is necessary when shutting down the one group of wheels, so that a mistake cannot be made.

Referring now to Fig. 3, the spindle 24 of 15 the valve-disk 25 carries a smaller valve-disk 26 which is displaceable thereon against the action of a coil spring 27 which normally holds the disk pressed against a collar 28 of the spindle 24. The collar 28 is at 20 such a distance from the larger valve-disk 25 that the smaller disk cannot be pressed against its seat 29 by the spring 27 in the closed position of the disk 25 shown in Fig. 3. The valve chamber is therefore connected 25 with the recess 30 of the guide 35 of the valve-spindle, so that the steam leaking past the valve-disk 25 or otherwise can flow the shortest way through the pipe 9 to the exhaust chamber 4. When the valve-disk 25 30 is lifted from its seat when cutting in the group of wheels, the valve-disk 26 is at once seated and is pressed the more firmly on its seat by the spring 27 the farther the valve is opened.

35 The valve-disk 25 is preferably provided with a piston-like shoulder 32. The object of this is to keep the valve closed, when lifting the disk 25 from its seat, until the disk 26 is seated, in order that, when changing 40 over, no steam may uselessly pass directly from the supply-pipe to the pipe 9. The same is the case when closing the valve-disk 25.

The member used for controlling the connection of the exhaust chamber 4 or the condensing plant with the admission port of 45 the group of wheels which can be shut down may be arranged, for example, in the pipe 9 or at its delivery end, and be influenced alone 50 directly by hand or automatically without departing from the scope of the invention.

What I claim as my invention and desire to secure by Letters Patent is:—

1. In a steam turbine having one or more 55 wheel-groups capable of being shut off separately from the whole turbine and steam admission valve for the same, a controllable by-pass interconnecting the steam admission space before a wheel-group but behind

the steam admission valve of said wheel-group with the lower pressure space behind this wheel-group.

2. In a steam turbine having one or more wheel-groups capable of being shut off separately from the whole turbine, and having steam admission valves, a by-pass interconnecting the steam admission space before a wheel-group but behind the steam admission valve of said wheel-group with the lower pressure space behind this wheel-group means controlling said by-pass, and means interconnecting said controlling means and the steam admission valve of the said wheel-group.

3. In a steam turbine having one or more wheel-groups capable of being shut off separately from the whole turbine and having steam admission valves, and a valve spindle supporting said valves and provided with passages, a by-pass interconnecting the steam admission space before a wheel-group but behind the steam admission valve of said wheel-group with the lower pressure space behind this wheel group, said spindle with its passages forming part of said by-pass.

4. In a steam turbine having one or more wheel-groups capable of being shut off separately from the whole turbine and having steam admission valves and a valve spindle supporting said valves, a by-pass interconnecting the steam admission space before a wheel-group but behind the steam admission valve of said wheel-group with the lower pressure space behind this wheel-group, said spindle serving as means controlling said by-pass.

5. In a steam turbine having one or more wheel-groups capable of being shut off separately from the whole turbine and having steam admission valves, a by-pass interconnecting the steam admission space before a wheel-group but behind the steam admission valve of said wheel-group with the lower pressure space behind this wheel group at the other side of the same, means controlling said by-pass, and means interconnecting said controlling means and the steam admission valve of the said wheel-group, the by-pass being closed when the admission valve is open and being open when the admission valve is closed.

In testimony whereof I affix my signature in presence of two witnesses.

WILLIBALD GRUN.
